UNITED STATES PATENT OFFICE.

HARMON F. NOTBOHM, OF JANEVILLE, ASSIGNOR TO CALEB N. HARRISON,
OF MILWAUKEE, WISCONSIN.

CAR-BRAKE.

SPECIFICATION forming part of Letters Patent No. 269,103, dated December 12, 1882.

Application filed August 31, 1882. (No model.)

To all whom it may concern:

Be it known that I, HARMON F. NOTBOHM, of Janesville, in the county of Rock, and in the State of Wisconsin, have invented certain new and useful Improvements in Car-Brakes; and I do hereby declare that the following is a full, clear, and exact description thereof.

My invention relates to railway-car brakes, and is in part an improvement on the invention patented to me on the 15th day of August, 1882, numbered 262,690; and it consists in certain peculiarities of construction, as will be more fully set forth hereinafter.

In the drawings, Figure 1 is a side elevation, showing a portion of the floor-beams of a car, with beams and brake-shoes and their hangers, but with the rest of the truck omitted. Fig. 2 is a cross-section on the line xx of Fig. 1. Fig. 3 is a longitudinal vertical section of my entire device, and Fig. 4 is a detail view of the take-up.

In order to better understand my present improvement, I hereby refer to my above-named patent, with the understanding that in all respects, except those features herein specially noted as different, the parts of this device are identical with similar parts shown in said prior patent, and this reference will greatly simplify the task of description, the present Fig. 3 corresponding (except in said details of improvements hereinafter to be noted) to the left-hand portion of Fig. 1 of said patent, while the right-hand portion of Fig. 1 in said patent and the connection between front and rear trucks, (shown in Fig. 2 of said patent,) though not here shown, are to be understood as being the same, save only the details of improvements in the brake-hangers and the addition of the take-up.

Referring to the drawings, (and dispensing with the letters A to E, inclusive, as these refer to parts shown in the said prior patent, but not herein illustrated,) F designates the long rod extending the whole length of each car, and G is the bottom or platform of a car having trucks and wheels of ordinary construction, requiring no further description.

H H' are the brake-beams, preferably suspended from the platform or bottom of the car by hinged rods I.

K is a lever pivoted to a beam on the under

side of the platform G, one end of which lever is secured to the rod F, while a doubled or endless chain, L, is likewise attached at its center to the said lever K.

M and N are bars, and m, n, and o links, and m' n' pivotal points, all as described at length in my said prior patent, and requiring no further description here, while similarly P is the old hand-brake, connected with the nearest bar, M, by rod and chain p, while another rod and chain, Q, connects the bar N on that end of the car with the bar M on the other end of the car, (not shown,) so as to utilize my invention with the existing style of car having hand-brakes, all as described in said prior patent.

Having thus briefly explained what is old, I will now point out the new features wherein I now seek protection.

R R represent my spring-hangers, and which may be bent into the shape shown either at the left or at the right of Fig. 1, (though I prefer the latter form;) or any modified form of spring may be substituted therefor. As shown, these hangers are suspended from the under side of the platform G, and at a point preferably in line with the brake-beams H H', I secure to said hangers the brake-shoes h h', and then the said springs are curved around into substantially U shape, and to the outside stem of each U I attach the brake-beams H and H', as shown.

S S represent braces or buffers projecting down from the platform G, with their lower ends bent so as to come in contact with the described spring-hangers R R, and serving as fulcra to prevent the bending of the springs above the said points of contact.

It now remains to describe the other improvement—namely, the take-up shown at the left of Fig. 3 and in detail in Fig. 4. It consists primarily of the hanger T, suspended from below the platform G, and in which is pivoted the upper sheave, U, while its lower portion is wider and forms ways tt for the sliding blocks v v, which are connected by the shaft v', and thus support between them the lower sheave, V, on said shaft. The chain of the long rod F is passed outwardly over the top of the upper sheave, U, and then back between the sheaves and under the lower sheave, V, and forward again, terminating in a rod and hook or equiv-

alent device for connecting it with the end of the attachments to the rod F of the next car. The sliding blocks are connected at their outer ends with the shank of the buffer W, which shank passes through the end beam of the car, as shown in Fig. 3, and the take-up is automatically operated whenever the head of this buffer comes in contact with the head of the buffer W' of another car, which will force the sliding blocks inward, bearing with them the lower sheave, V, and hence take up the slack of the chain—a feature of great importance, inasmuch as without such take-up the connections would hang loosely between the cars when the buffers of two cars were brought or forced together, (as in stopping or going downgrade, &c.,) and hence in such event the brake-rods would not work so long as the chains were slack. Again, when the cars were started the connection would be tightened with a jerk, thereby tending to breakage of the pins and links or other couplings, which is wholly obviated by my device.

The advantages of my spring-hangers R over those of ordinary construction are that they permit of a sufficient pressure of the brake-shoes to arrest the momentum of the wheels and so stop the car, while at the same time they yield sufficiently to allow the said wheels to turn, and thereby sliding or skidding is prevented and the wheels saved from uneven wear.

In place of the braces S, any of the old systems—such as using springs for throwing the brake-shoes off the wheels, or such as hanging the shoes at an angle that will clear the wheels—may be employed; but I prefer to use these braces in ordinary cases.

The spring-hangers R may be, if desired, simply vertical, with the shoes and brake-beams attached at different points thereto, and hence the rods I are not absolutely necessary to support the said brake-beams; but I prefer to use

them to guard against possible breakage or accident.

With respect to the take-up, I do not limit myself to the exact construction shown in the drawings, as it may be indefinitely varied in detail without departing from the spirit of my invention; and it is to be understood that there is a take-up at each end of each car as well as on the tender and engine, when desired.

Having thus described my invention, what I claim as new, and desire to secure by Letters Patent, is—

1. The spring-hanger carrying the brake-shoe, and having an elastic extension secured to the brake-beam, substantially as described.

2. The combination, with a spring-hanger, of the shoe and brake-beam attached at different points to said hanger.

3. The combination of a swinging brake-beam, a swinging spring-hanger, a brake-shoe, and a brace or buffer adapted to serve as a fulcrum to said spring-hanger, substantially as set forth.

4. The combination of the brake-rod connections of railroad-cars with an automatic take-up consisting of a hanger, bearing fixed sheave and sliding blocks bearing another sheave, said blocks being connected with a buffer, substantially as set forth.

5. The automatic take-up described, consisting of hanger T, with ways t t, fixed sheave U, and sliding blocks v v, bearing sheave V, and connected to buffer W, substantially as set forth.

In testimony that I claim the foregoing I have hereunto set my hand on this 25th day of August, 1882, in the presence of two witnesses.

HARMON F. NOTEBOHM.
